PAGE 3

Fig. 3.

Fig. 4.

Figure 1 is a perspective view of my new design for a packaged compressor unit as it appears from a position off the right rear corner thereof;

Figure 2 is a perspective view of such unit as it appears from a position off the left rear corner thereof;

Figure 3 is an end view taken from the right of Figure 1; and

Figure 4 is a plan view of such unit.

I claim:

The ornamental design for a packaged compressor unit, substantially as shown.
